His Attorney

UNITED STATES PATENT OFFICE.

OLE K. KJOLSETH, OF SCOTIA, NEW YORK, ASSIGNOR TO GENERAL ELECTRIC COMPANY, A CORPORATION OF NEW YORK.

RAILWAY TRUCK.

Application filed August 12, 1927. Serial No. 212,591.

My invention relates to railway trucks for locomotives or cars, and has for its object the provision of an improved truck in which the frame of the truck is spring supported on the axles and free to tilt laterally relative thereto without subjecting the frame to torsional stresses or reducing the hub thrust wearing surfaces against the pedestal shoe.

My invention will be more fully set forth in the following description referring to the accompanying drawing and the features of novelty which characterize my invention will be pointed out with particularity in the claim annexed to and forming a part of this specification.

In the drawing Fig. 1 is a transverse section of a truck embodying my invention taken approximately on the line 1—1 of Fig. 2; Fig. 2 is a side elevation of a portion of the truck; and Fig. 3 is a sectional view on the line 3—3 of Fig. 2.

Referring to the drawing, the truck in connection with which I have illustrated my invention comprises wheels 10 and wheel axles 11 provided with journals 12 on which are arranged journal boxes 13 for supporting the truck frame. This truck frame may be of any convenient form but in the present instance comprises side frames 14 having pedestal yokes 15 extending about the journal boxes 13. In accordance with my invention the side frames 14 are guided relative to the journal boxes by cylindrical guide members 16 which are grooved at 16^a to slidably engage the pedestal yokes and which extend into cylindrical recesses 13^a in the journal boxes to which they conform, the groove 16^a and the surface of the cylindrical recess 13^a being provided with a covering of suitable bearing metal 16^b, such as pressed steel, which may be renewed when the surfaces become worn. These guide members slide freely on the pedestal yokes and turn freely in the cylindrical recesses in the journal boxes so that the wheel axles 11 are guided in their vertical movement relative to the pedestals without restricting the tilting of the wheel axles transversely

relative to the truck frame. By pivotally supporting the guide member 16 in the journal box in this manner I am enabled to provide a large bearing surface in the groove 16^a which conforms closely to the pedestals 15 of the side frames 14, and at the same time obtain the necessary flexibility between the journal box and the pedestal to permit swaying of the frame on the axle or tilting of the axle relative to the frame without twisting the side frame 14 and without subjecting the surfaces of the guide member to excessive wear. I have shown the truck frame supported on the journal boxes 13 by means of equalizers 17 which are yieldably supported on the journal box by springs 18 and which are spring supported on the side frames 14 between the truck axles thereof, the details of the supporting connections between the equalizers and the frame not being shown as they form no part of my invention.

It is apparent that in this construction if swaying of the truck frame or unevenness in the track should cause the wheel axles 11 to tilt transversely relative to the frame that the wearing surfaces between the guide member 16 and the journal box or the pedestal are not reduced and that the side frames 14 will not be subjected to any torsional stresses because the members 16 which guide the journal boxes relative to the pedestal yokes 15 are pivotally supported in the cylindrical recesses in the journal boxes.

Various modifications will occur to those skilled in the art of the embodiment of my improved truck construction herein disclosed. I desire it to be understood, therefore, that my invention is not limited to the particular arrangement shown and described, and I intend in the appended claim to cover all modifications which do not depart from the spirit and scope of my invention.

What I claim as new and desire to secure by Letters Patent of the United States, is:

A locomotive or car truck comprising wheels and wheel axles, boxes for receiving the journals of said wheel axles, side frames

having pedestal yokes extending about said boxes, means including springs for supporting said side frames on said boxes, said boxes having cylindrical recesses therein,
5 cylindrical guide members extending into the recesses in said boxes and having a grooved portion projecting therebeyond, said

pedestal yokes being arranged to slidably engage the grooves in said guide members so as to permit tilting of said frame transversely relative to said axles. 10

In witness whereof, I have hereunto set my hand this 11th day of August, 1927.

OLE K. KJOLSETH.
